UNITED STATES PATENT OFFICE

171,715

HOSIERY DISPLAY DEVICE

Robert Kayton, Jackson Heights, Walter Freundel, Brooklyn, Harry R. Jeter, New York, and Beatrice Dudek, Garden City, N. Y., assignors to Chadbourne Sales Corporation, a corporation of New York

Application July 29, 1953, Serial No. 26,182

Term of patent 14 years

(Cl. D80—9)

To all whom it may concern:

Be it known that we, Robert Kayton, a citizen of the United States, residing at Jackson Heights, in the county of Queens and State of New York, Walter Freundel, a citizen of the United States, residing at Brooklyn, in the county of Kings and State of New York, Harry R. Jeter, a citizen of the United States, residing at New York, county of New York, and State of New York, and Beatrice Dudek, a citizen of the United States, residing at Garden City, in the county of Nassau, and State of New York, have invented a new, original, and ornamental Design for a Hosiery Display Device, of which the following is a specification, reference being had to the accompanying drawings, forming part thereof, in which:

Fig. 1 is a perspective view of a hosiery display device, showing our new design;

Fig. 2 is a plan view thereof; and

Fig. 3 is a side elevation as seen from the left on the perspective axis of Fig. 1.

We claim:

The ornamental design for a hosiery display device, as shown.

ROBERT KAYTON.
WALTER FREUNDEL.
HARRY R. JETER.
BEATRICE DUDEK.
